E. S. COOK

TRAIN CONTROL DEVICE

Filed July 23, 1927.

Patented June 26, 1928.

UNITED STATES PATENT OFFICE.

EARLE S. COOK, OF WILMERDING, PENNSYLVANIA, ASSIGNOR TO THE WESTINGHOUSE AIR BRAKE COMPANY, OF WILMERDING, PENNSYLVANIA, A CORPORATION OF PENNSYLVANIA.

TRAIN-CONTROL DEVICE.

Application filed July 23, 1927. Serial No. 207,840.

This invention relates to automatic train control apparatus and more particularly to that type having means for automatically effecting a brake pipe reduction in two stages.

In the pending application of Thomas H. Thomas and Earle S. Cook, Serial No. 109,044, filed May 14, 1926, means are disclosed for automatically effecting a split or two stage reduction in brake pipe pressure, whenever the train control apparatus operates to make a brake application on the train.

Whether or not a two stage reduction in brake pipe pressure is required for applying the brakes on a train, is mainly dependent upon the train speed. If the train speed is low, the retarding force on the train, caused by applying the brakes, develops much more rapidly than if the train speed is high, so that as a result, when the train speed is high, the brakes may be applied by effecting a single and full reduction in brake pipe pressure, without causing any damage to the train.

The principal object of my invention is to provide means for automatically preventing the split reduction device from effecting a two stage reduction in brake pipe pressure, in case the brakes are automatically applied by a change in signal indication, when a train is operating in territory governed by a high speed signal indication.

In the accompanying drawing, the single figure is a diagrammatic view of a train control apparatus, embodying my invention.

As shown in the drawing, the apparatus may comprise a speed governor device 1, a speed valve device 2, an application valve device 3, and equalizing piston device 4, a medium speed magnet valve device 5, a high speed magnet valve device 6, and a split reduction valve device.

The speed governor device 1 comprises a governor 7, of the usual centrifugal type, adapted to be rotated according to the train speed and in operation is adapted to cause movement of a crosshead 8, carrying a plurality of tappets adapted to operate corresponding valves at various train speeds, such as a medium speed application valve 9 and a low speed application valve 10.

The speed valve device 2 comprises a high speed piston 11 contained in a chamber 12

and a slide valve 13 contained in a chamber 14 and adapted to be operated by said piston, which piston is opposed in outward movement by the pressure of a coil spring 15. Said speed valve device further comprises a medium speed piston 16, contained in a chamber 17, and a slide valve 18 contained in the chamber 14 and adapted to be operated by said piston. The piston 16 is opposed in outward movement by the pressure of a coil spring 19, contained in the piston chamber 17.

The application valve device 3 comprises a casing having a chamber 20, containing a piston 21 and a chamber 22 containing a slide valve 23, adapted to be operated by said piston, which piston is opposed in outward movement by the pressure of a spring 24.

The equalizing piston device 4 comprises an equalizing piston 25 forming, at one side, a chamber 26 connected to the usual equalizing reservoir 27 through pipe 28 and at the opposite side a chamber 29 connected to the usual brake pipe 30. Said piston is adapted to operate a brake pipe discharge valve 31 to operate a brake pipe discharge valve 31 for venting fluid under pressure from the brake pipe 30 to the atmosphere.

The medium speed magnet valve device 5 comprises a magnet and valves 32 and 33, operable by said magnet. The high speed magnet valve device 6 comprises a magnet and valves 34 and 35, operable by said magnet.

The split reduction valve device is similar to that disclosed in the pending application of Thomas H. Thomas and Earle S. Cook, Serial No. 109,044, filed May 14, 1926, and comprises a control portion 36 and a hold-back portion 37. The control portion 36 comprises a piston 38 contained in a chamber 39 and a piston 40 contained in a chamber 41, said pistons having different areas, being connected together by a stem and being adapted to cooperate in operating a slide valve 42, contained in a chamber 43, 100 formed intermediate said pistons. The hold-back portion 37 comprises a piston 44, contained in a chamber 45, and a slide valve 46, contained in a chamber 47 and adapted to be operated by said piston. Inward movement of said piston and slide valve is opposed by the pressure of a coil spring 48 against a thrust washer 49, engaging the end

of the piston stem. Said spring and washer are contained in a chamber 86 connected to the atmosphere through a passage 74 in the casing and connected to the valve chamber 47 through openings 88 formed in the piston guide portion 87.

In operation, fluid under pressure is supplied from a main reservoir 50 to a feed valve device 51, which is adapted to reduce the pressure of said fluid to that employed in the brake pipe 30 and in the operation of the train control apparatus. Fluid at said reduced pressure is supplied from said feed valve device to pipe 52, from whence it flows to the speed valve chamber 14, the application valve chamber 22, to the seat of the application slide valve 23 and to the chambers containing the magnet valves 33 and 35. With the application slide valve 23 in release position, as shown in the drawing, cavity 53 therein registers with passage 52, so that fluid from said passage flows through the cavity 53 to the brake pipe 30, charging said brake pipe and from said cavity also through passage and pipe 54 to chamber 26 of the equalizing piston device 4 and from said chamber to the equalizing reservoir 27 through pipe 28. Fluid under pressure is supplied from the brake pipe 30 to the equalizing piston chamber 29. The fluid pressures thus being equal on the opposite sides of the equalizing piston 25, the discharge valve 31 is held seated. Brake pipe fluid being supplied to the control piston chamber 41 of the split reduction device, the control pistons 38 and 40 and slide valve 42 are held in their upper position, as shown in the drawing, since the control piston chamber 39 is normally vented to the atmosphere through pipe and passage 55 and the atmospheric choke plug 56. With the control portion 37 of the split reduction device in this position, the piston chamber 45 of the hold-back portion 37 is vented to the atmosphere through passage and pipe 57, cavity 58 in the control portion slide valve 42 and the choke plug 59, so that the pressure of spring 48 holds the hold-back piston 44 and slide valve 46 in the position shown in the drawing, in which position a first reduction reservoir 60 is connected to a second reduction reservoir 61, through pipes and passages 62 and 63 and a cavity 64 formed in the hold-back slide valve 46. With the application slide valve in release position, said reduction reservoirs are both vented to the atmosphere through pipes and passages 62 and 63, cavity 65 in the application slide valve 23 and an atmospheric exhaust passage 66.

When a train is operating in territory governed by a high speed signal indication, the magnet of the high speed magnet valve device 6 is energized and holds the valve 34 seated and the valve 35 unseated,

while the magnet of the medium speed magnet valve device 5 is deenergized, so that the valve 32 is unseated and the valve 33 seated. With the high speed magnet valve 34 seated and the valve 35 unseated, fluid at feed valve pressure flows from the chamber containing the valve 35 to the high speed valve piston chamber 12. The fluid pressure thus becomes equal on the opposite sides of the high speed piston 11, and the pressure of spring 15 holds said piston and the slide valve 13 in the position shown in the drawing, in which, a port 67 through the slide valve 13 registers with a passage 68 in the seat, through which fluid is supplied to the medium speed piston chamber 17. The fluid pressure thus becomes equal on the opposite sides of the medium speed piston 16, so that the pressure of the coil spring 19 will hold said piston and the slide valve 18 in the position shown in the drawing.

With the high speed slide valve 13 in the inner position, fluid under pressure is supplied from the valve chamber 14 to the application piston chamber 20 through the passage and pipe 70. Fluid under pressure is also supplied to said piston chamber from the application valve chamber 22 through the port 69 in the application piston 21, so that the fluid pressure on the opposite sides of said application piston 21 becomes equalized and the pressure of spring 24 holds said piston and the slide valve 23 in the release position, as shown in the drawing.

With the control pistons 38 and 40 and slide valve 42 of the split reduction device in the upper position, a timing reservoir 71 is vented to the atmosphere through pipe and passage 72, past a ball check valve 73 and through the atmospheric choke plug 59. The chamber 47 of the hold-back portion of the split reduction device is open to the atmosphere by way of the opening 88 through the piston guide 87 and chamber 86, which is provided with an atmospheric vent port 74, and since in the position described, passage 72 is open to chamber 47, the timing reservoir 71 is also vented to the atmosphere by way of port 74.

If the signal indication changes from high speed to medium speed, the high speed magnet becomes deenergized, thereby permitting the valve 35 to seat and the valve 34 to become unseated, so that fluid under pressure from the high speed piston chamber 12 is vented to the atmosphere through pipe and passage 75 and past the open valve 34. The fluid pressure in the speed valve chamber 14 then shifts the high speed piston 11 and slide valve 13 to the outward position in which, cavity 76 connects passage and pipe 70 from the application piston chamber 20 to passage and pipe 77 connected to the chamber containing the governor medium speed valve 9, which valve is unseated

when the speed of the train exceeds the medium speed limit. The application piston chamber 20 is thus vented to the atmosphere, which permits the fluid pressure in the application valve chamber 22 to shift the application piston 21 and slide valve 23 to the outer or application position.

With the application slide valve 23 in application position, the supply of fluid at 10 feed valve pressure to the brake pipe 30, to the equalizing piston chamber 26, and to the equalizing reservoir 27 is cut off and the brake pipe is disconnected from said piston chamber and reservoir. The atmospheric 15 vent of the first and second reduction reservoirs 60 and 61, respectively, through cavity 65 is also cut off and the equalizing reservoir 27 and equalizing piston chamber 26 are connected to the first reduction reservoir 60 20 through pipe and passage 54, cavity 65 in the slide valve and passage and pipe 62. Fluid under pressure from the equalizing reservoir 27 then flows to the first reduction reservoir 60, causing a reduction in equalizing 25 reservoir pressure. The equalizing piston device 4 then operates in the well known manner to cause a corresponding reduction in brake pipe pressure. The fluid discharged from the brake pipe 30 by the 30 equalizing piston device 4 is vented into passage 55 and then to the atmosphere through the atmospheric choke plug 56. The capacity of said choke plug is less than the rate of flow past the opened discharge 35 valve 31, so that a pressure builds up in passage 55. Since said passage is connected to the control piston chamber 39, a corresponding pressure is built up therein and acts to shift the control pistons 38 and 40 40 and slide valve 42 to the downward position, in which, the hold back piston chamber 45 is connected through passage and pipe 57 and cavity 58 in the slide valve 42, to passage and pipe 81 leading to the seat of the 45 medium speed slide valve 18.

With the high speed slide valve 13 in the outward position, a cavity 78, therein, connects passage 68 from the medium speed piston chamber 17 to passage and pipe 79 leading to the medium speed magnet valve device 5. Since the magnet of said device is energized in territory governed by a medium speed signal indication, the valve 32 is seated and the valve 33 is unseated, 50 so that fluid under pressure from pipe 52 is supplied to the medium speed piston chamber 17 through pipe and passage 79, cavity 78 in the high speed slide valve 13 and passage and pipe 68, thereby maintaining 55 the medium speed piston 16 and slide valve 18 in the inner position, in which position, a cavity 80, therein, connects passage and pipe 81 from the split reduction device to the atmospheric passage 82. Since the hold-back piston chamber 45 is connected to the 60

passage 81, when the control pistons 38 and 40 and slide valve 42 are in the downward position, said piston chamber 45 is maintained at atmospheric pressure during the first reduction in brake pipe pressure. The 70 pressure of spring 48 therefore holds the holdback piston 44 and slide valve 46 in the position shown in the drawing, in which, the first and second reduction reservoirs 60 and 61 are connected, so that the fluid from 75 the equalizing reservoir flows to both of said reduction reservoirs and causes a continuous and complete service reduction in the equalizing reservoir pressure.

If a train is operating above a low speed 80 limit in territory governed by a medium speed signal indication, the governor medium speed valve 9 is seated, thereby preventing the venting of fluid from the application piston chamber 20, and the governor low 85 speed valve 10 is unseated. If the signal indication then changes to a low speed, the magnet of the medium speed valve device 5 becomes deenergized and the magnet of the high speed magnet valve device 6 remains deenergized, as in territory governed by a medium speed signal indication. Deenergization of the first mentioned magnet 90 permits valve 33 to seat and valve 32 to be unseated, which permits a venting of the 95 fluid under pressure from the medium speed piston chamber 17, by way of passage 68, cavity 78 in the high speed slide valve 13 and pipe and passage 79. The fluid pressure in the speed valve chamber 14 then 100 shifts the medium speed piston 16 and slide valve 18 to the outward position, in which, the application piston chamber 20 is vented to the atmosphere through passage 70, cavity 83 in the medium speed slide valve 18, 105 passage and pipe 84 and past the unseated governor valve 10. The application piston 110 21 and slide valve 23 are then shifted to the outer or application position and an application of the brakes is initiated in the same manner as hereinbefore described.

In the outward position of the medium speed slide valve 18, the cavity 85 in said slide valve connects passage 52 from the feed valve device 51 to passage 81 leading to the seat of the control slide valve 42 of the split reduction device, so that when the control pistons 38 and 40 shift the slide valve 42 to the downward position, upon initiation of the first reduction, fluid under pressure from passage 81 is permitted to flow through cavity 58 in said slide valve and passage 57 to the hold-back piston chamber 45 and shift the hold-back piston 115 44 and slide valve 46 to the inner position and thus disconnect the passages 62 and 63 from the first and second reduction reservoirs 60 and 61, respectively, so that the degree of the first reduction in equalizing 120 reservoir pressure will be limited to the 125 130

decrease caused by the equalization into the first reduction reservoir.

Fluid under pressure supplied to passage and pipe 57 leading to the hold-back piston chamber 45 also flows from said pipe through a choked passage 89 and pipe and passage 72 to the timing reservoir 71, and since passage 72 from the timing reservoir is lapped by the hold-back slide valve 46 in the inner position, said reservoir becomes charged.

When the first reduction in brake pipe pressure is completed and the discharge valve 31 is seated, the fluid under pressure from the control piston chamber 39 is then vented to the atmosphere through pipe and passage 55 and the choke plug 56. The control pistons 38 and 40 and slide valve 42 are then shifted to their upper position, by the brake pipe pressure in chamber 41, in which position the hold-back piston chamber 45 and the timing reservoir 71 are connected to the atmosphere through pipe and passage 57, cavity 58 in the slide valve 42 and the atmospheric choke plug 59. When the pressure of the fluid acting on the hold-back piston 45 is thereby reduced to a predetermined degree, the pressure of spring 48 shifts said piston and the slide valve 46 to the position shown in the drawing, in which position the cavity 64 in said slide valve connects the passages 62 and 63 leading to the first and second reduction reservoir 60 and 61 respectively. The fluid under pressure in the equalizing reservoir 27 and first reduction reservoir 60 then equalizes into the second reduction reservoir 61, causing a further predetermined decrease in said equalizing reservoir pressure. Since the pressure in chamber 26 of the equalizing piston device 4 also reduces a corresponding degree, said device then operates to cause a corresponding second reduction in the pressure of the brake pipe fluid.

During the second reduction, the hold-back portion 37 of the split reduction device is prevented from operating to again separate the two reduction reservoirs and thereby interfere with the second reduction, on account of the control pistons and slide valve being held in the upper position by the pressure of fluid from a lock-up reservoir 95, which is connected to the valve chamber 43 through pipe and passage 90 and cavity 91 in the slide valve 42, said lock-up reservoir becoming charged, while effecting the first reduction, by fluid under pressure from the brake pipe, which fluid flows thereto through passage 30, cavity 92 in the application slide valve 23, pipe and passage 93, cavity 94 in the control slide valve 42 of the split reduction device, and passage and pipe 90.

If a train is running above the medium speed limit in territory governed by a high speed signal indication and the signal indi-

cation changes to a low speed, the magnet valve devices 5 and 6 operate, in the manner hereinbefore described, to cause both the high speed and medium speed slide valves, 13 and 18 respectively, to be shifted to their outer position and thereby cause the application valve device 3 to initiate an application of the brakes. A two stage reduction is not obtained in this instance, however, even though the medium speed slide valve 18 is in the outer position, because the fluid under pressure that flows from the feed valve device through pipe 52 to port 85 in the medium speed slide valve 18 is vented to the atmosphere through the open governor valve 9, by way of passage and pipe 77, instead of being permitted to flow to the split reduction device through passage and pipe 81. If, however, a train is running below a medium speed limit in territory governed by a high speed signal indication and the signal indication changes to low speed, a split or two stage reduction is obtained in the same manner as when a brake application is effected on a train by a change from a medium speed signal indication to a low speed signal indication, since below medium speed the governor valve 9 is seated, so that the fluid supplied to passage and pipe 81, through port 85 in the medium speed slide valve 18, flows to the split reduction device which then operates in the manner hereinbefore described.

Having now described my invention, what I claim as new and desire to secure by Letters Patent, is:—

1. In an automatic train control apparatus, the combination with a brake pipe, of a timing reservoir, a valve device subject to the pressure in said reservoir for initiating a two stage reduction in brake pipe pressure, and a valve device operated according to the signal indication for supplying fluid under pressure to said reservoir in one position and for venting said reservoir to the atmosphere in another position.

2. In an automatic train control apparatus, the combination with a brake pipe, of a timing reservoir, a valve device subject to the pressure in said reservoir, for initiating a two stage reduction in brake pipe pressure, and a valve device operating when the signal indication is for high speed for venting said reservoir to the atmosphere and when the signal indication is for a lower speed for supplying fluid under pressure to said reservoir.

3. In an automatic train control apparatus, the combination with a brake pipe, of a timing reservoir, a valve device subject to the pressure in said reservoir for initiating a two stage reduction in brake pipe pressure, and a valve device operating when the signal indication is for high speed for venting said reservoir to the atmosphere and

when the signal indication is for low speed for supplying fluid under pressure to said reservoir.

4. In a fluid pressure brake, the combination with a brake pipe, of a valve device 5 operated by an increase followed by a decrease in fluid pressure for initiating a two stage reduction in brake pipe pressure, and means operated when the signal indication 10 is for a high speed for preventing an increase in pressure on said valve device and when the signal indication is for a lower speed for supplying fluid under pressure to said valve device.

15 5. In a fluid pressure brake, the combination with a brake pipe, of a valve device

operated by an increase followed by a decrease in fluid pressure for initiating a two stage reduction in brake pipe pressure, a 20 valve means normally connecting said valve device to the atmosphere and operated by fluid discharged in making a first reduction in brake pipe pressure for connecting said valve device to a passage, and a valve mechanism controlled by the signal indication 25 and having one position in which said passage is connected to the atmosphere and another position in which said passage is supplied with fluid under pressure.

In testimony whereof I have hereunto set 30 my hand.

EARLE S. COOK.
